ATTORNEY

UNITED STATES PATENT OFFICE.

HERBERT E. HELLER, OF MILWAUKEE, WISCONSIN, ASSIGNOR TO THE CUTLER-HAMMER MFG. CO., OF MILWAUKEE, WISCONSIN, A CORPORATION OF WISCONSIN.

CIRCUIT-CONTROLLING DEVICE.

Application filed November 20, 1922. Serial No. 602,118.

This invention relates to circuit controlling devices and is particularly applicable to enclosed switches of the safety type.

The invention has among its objects to provide a switch of the enclosed type having improved safety means associated therewith to insure opening of the switch prior to opening of the casing cover and to also insure against closure of the switch until after closure of the casing cover.

Another object is to provide a safety switch of the aforesaid character having improved operating means which is of simple, rugged and compact construction.

Another object is to provide a switch of the aforesaid character wherein the switch operating means is associated with the casing cover in a manner whereby the same serves to positively hold the casing cover in its open position.

Various other objects and advantages of the invention will hereinafter appear.

The accompanying drawing illustrates an embodiment of the invention which will now be described, it being understood that the embodiment illustrated is susceptible of modification without departing from the scope of the appended claims.

In the drawing,

Figure 1 is a front elevational view of a safety switch embodying the invention, the casing cover being shown in section;

Figs. 2 and 3 are sectional views each taken substantially on line 2-2 of Fig. 1 illustrating the switch in its closed and open positions; and

Fig. 4 is a similar sectional view of the switch with the cover in open position.

Referring to the drawing the same illustrates an insulating base 1 having a double pole knife switch 2 mounted on the front face thereof, said base being also provided with fuse sockets arranged immediately below the poles of said knife switch for receiving fuse plugs 3 and 4. Switch 2 is of a conventional type, the blades thereof being pivoted at their lower ends and being connected at their upper ends by an insulating cross member 5. The left hand

blade of switch 2 is adapted to establish circuit from a terminal 6 adjacent the upper edge of the base 1 through fuse plug 3 to a terminal 7 located adjacent the lower edge of said base while the right hand blade

thereof is adapted to establish circuit from a terminal 8 adjacent the upper edge of said base through fuse plug 4 to a terminal 9 adjacent the lower edge of said base. Base 1 is secured to the rear wall of a box-shaped enclosing casing 10 by screws 11 and said casing is provided with a flanged cover 12 which is hinged thereto by a pivot pin 13.

Switch 2 is adapted to be operated through the medium of a toggle including links 14 and 15. Link 14 has one end pivotally connected by pin 16 to a bracket 17, secured by bolts 18 to the under side of the cross member 5. The opposite end of link 14 is pivotally connected to one end of the link 15 by a pin 19 and the opposite end of the latter link is fixed to an operating rod 20 by a cotter pin 21. Rod 20 is rotatably mounted within an opening in a bracket 22 fixed to the inner face of casing cover 12 and said rod projects outwardly through an opening in the side flange of said casing cover and is bent upwardly to provide a crank portion 23, which has an operating knob 24 secured to the upper end thereof. For a purpose hereinafter set forth the pivot pin 16 is connected by a helical spring 25 to rod 20 and the lower end of link 14 is provided with a lateral projection 26 adapted to engage the side face of link 15 upon setting of the toggle.

From the foregoing it is apparent that with the parts in the position shown in Fig. 3, spring 25 serves to bias switch 2 outwardly, such outward movement being limited by engagement of the link 14 with the inner face of casing cover 12. However, upon rotation of the crank portion 23 towards the rear of casing 10 links 14 and 15 are moved into alignment to effect closure of the switch. Stop 26 is arranged to permit movement of said links slightly beyond their aligned position to thereby prevent opening of the switch under the action of spring 25. However, upon forward rotation of the operating handle to a degree sufficient to move links 14 and 15 out of alignment spring 25 will tend to open switch 2 with a snap action.

To insure against opening of the casing cover while switch 2 is in closed position and to also insure against closure of the switch until after closure of said cover the operating member 20 has fixed thereto a

- projecting arm 27 having a slot 28 in the under side thereof for receiving a pin 29 fixed to the left hand wall of casing 10. As shown in Fig. 2 the angular position of arm 27 with respect to rod 20 is such that when the toggle mechanism is set slot 28 receives pin 29 to prevent opening of casing cover 12. However, as shown in Fig. 3 upon opening of the switch, arm 27 is moved out of locking engagement with pin 29 to permit opening of casing cover 12.
- Referring now to Fig. 4 it will be observed that when cover 12 is swung outwardly to a given position to permit access to the interior of the casing 10 links 14 and 15 and the switch blades 2 will be moved into substantial alignment to positively hold said cover against closing movement. With the parts positioned as shown in Fig. 4 closure of the cover can be readily effected after operation of the operating rod 20 in a direction to move links 14 and 15 out of alignment. It should be noted that if the toggle links 14 and 15 are set during closing movement of cover 12 the left hand end of arm 27 will abut pin 29 to prevent inward movement of said cover to a position wherein the switch will be closed.

Cover 12 is provided with an operating knob 30 on the lower flange thereof and the same is also provided with means for releasably restraining the same in closed position such means including inwardly struck portions 31 on the side flanges of said cover and co-operating recesses 32 in the side walls of the casing 10. Casing 10 can be designed in numerous ways and in the embodiment illustrated the rear wall thereof is provided with conductor openings 33 and 34 adjacent terminals 7 and 8 while the bottom wall thereof is provided with an opening 35 for receiving a conduit fitting 36.

I claim:

1. In a circuit controlling device, in combination, an enclosing casing comprising a body portion and a cover pivotally secured thereto, a unitary switch device mounted in said body portion, a switch operating member carried by said cover and movable independently of the latter, and a permanent operating connection between said member and said device.

2. In a circuit controlling device, in combination, an enclosing casing comprising a body portion and a cover pivotally secured thereto, a unitary switch device mounted in said body portion, a switch operating member carried by said cover, and a toggle connecting said operating member to said device.

3. In a circuit controlling device, in combination, an enclosing casing comprising a body portion and a cover pivotally secured thereto, a unitary switch device mounted in said body portion, said device including an

insulating base having cooperating stationary and movable contacts mounted thereon, an oscillatable operating member mounted on said cover, a toggle connecting said operating member to the movable contacts 70 of said device and a spring associated with said toggle to provide for opening of the movable contacts of said device with a snap action.

4. In a circuit controller, in combination, 75 an enclosing casing comprising a body portion and a cover pivotally secured thereto, a unitary switch device mounted in said body portion, said device including an insulating base having cooperating stationary and movable contacts mounted thereon, an oscillatable operating member mounted on said cover, an operating connection 80 between said member and the movable contacts of said device and means associated with said operating member for locking said cover in closed position upon closure of the movable contacts of said device, said means including a locking part fixed to said body portion and a cooperating part fixed to said operating portion.

5. The combination with a switch including a movable contact element of an enclosing casing therefor including a pivoted cover an oscillatable operating member mounted on said cover a toggle operating connection between said operating member and the movable element of said switch, said toggle and the movable element of said switch being adapted to co-operate upon 100 opening of said cover to positively hold the latter in open position.

6. In combination a knife switch an insulating supporting base therefor fuses mounted on said base, a box-shaped enclosing casing for said parts a cover hinged to said casing an oscillatable operating member mounted on said cover and a toggle connection between said operating member and the movable element of said knife switch to effect opening and closure of said knife switch upon movement of said operating member in opposite directions.

7. In combination a knife switch an insulating supporting base therefor fuses mounted on said base, a box-shaped enclosing casing for said parts a cover hinged to said casing an oscillatable operating member mounted on said cover and a toggle connection between said operating member and the movable element of said knife switch to effect opening and closure of said knife switch upon movement of said operating member in opposite directions and means 115 associated with said operating member for locking said cover in closed position upon closure of said knife switch.

8. The combination with a knife switch of an enclosing casing therefor a cover pivoted to said enclosing casing an oscillatable

operating member mounted on said cover a
toggle connecting said operating member
and the movable element of said knife
switch to effect opening and closing of said
switch to effect opening and closing of said
switch and said knife switch and said operating
member tending to oppose setting of said
toggle and tending to effect opening of said 10
switch with a snap action.

5 knife switch upon movement of said operat-
ing member in opposite directions and a
spring connection between the movable ele-
ment of said knife switch and said operating
member tending to oppose setting of said
toggle and tending to effect opening of said 10
switch with a snap action.

In witness whereof, I have hereunto sub-
scribed my name.

HERBERT E. HELLER.
